UNITED STATES PATENT OFFICE.

GEORGE P. ELMEN AND GEORGE SHARPNACK, OF LINCOLN, NEBRASKA; SAID SHARPNACK ASSIGNOR TO SAID ELMEN.

VIBRATOR.

1,269,803.

Specification of Letters Patent. Patented June 18, 1918.

Application filed July 20, 1917. Serial No. 181,815.

To all whom it may concern:

Be it known that we, GEORGE P. ELMEN and GEORGE SHARPNACK, citizens of the United States, residing at Lincoln, in the 5 county of Lancaster and State of Nebraska, have invented certain new and useful Improvements in Vibrators, of which the following is a specification.

Our invention relates to certain new and 10 useful improvements in vibrators especially those of the massage type, and the invention primarily has for its object to provide a vibrator in which two distinctly different strokes, one a percussion stroke and the 15 other a "brushing" stroke, can be obtained or a combination of the strokes may be had.

Another object of our invention is to provide a device of this character of a simple and effective construction which will greatly 20 increase the effective uses to which the vibrator can be put, and thereby increase the commercial value of the same.

In its generic nature the invention comprises a vibrator having an applicator arm 25 to which the various applicator instruments are attached, as desired, a motor including a rotating crank drive being connected with the applicator arm through a special shiftable connection so designed and arranged 30 that either a percussion stroke or a "brushing" stroke can be given to the applicator arm, as desired, the driving connection being such that a combination of the two strokes mentioned may be had, if desired.

In its more subordinate nature, the invention 35 also includes those novel details of construction, combination and arrangement of parts, all of which will be first fully described, then be specifically pointed out in the appended claims and illustrated in the accompanying drawings, in which:—

Figure 1 is a perspective view illustrating the invention.

Fig. 2 is a front elevation of the same.

Fig. 3 is a longitudinal section on substantially the line 3—3 of Fig. 2, parts being in elevation.

Fig. 4 is a cross section thereof on the line 4—4 of Fig. 3, parts being positioned to impart a rubbing or brushing motion to the applicator instrument.

Fig. 5 is a similar view, the parts being positioned to impart a vibrating or percussion stroke to the applicator arm.

Fig. 6 is a section on the line 6—6 of 55 Fig. 3.

Fig. 7 is a detail view illustrating a spring tension device for holding the shifting indicator arm to its different positions with retaining friction.

In the drawings, in which like letters and numeral of reference indicate like parts in all of the figures, 1 is the driving motor, (preferably electrical) having a supporting casing, the front section 2 of which is designed to support the operating parts of the vibrator. 3 indicates the housing for the vibrator mechanism and this housing is open at 4 and secured to the front of the motor casing 2 by screws to close the opening 4. The housing 3 has a neck 6 which is provided with a semi-spherical bearing surface 7 for the ball bearing portion 8 of the hollow guide bushing 9 in which the applicator arm 10 has its reciprocating movement. A leather packing 11 is interposed between the ball 8 and the seat 7 and the ball is held to its seat by a spring 12 and bushing 13, the latter being threaded into the end of the neck 6, as best shown in Fig. 4 of 80 the drawing. The applicator arm 10 is provided with a fork 14 to carry the bearing pin 15 to which the links 16 and 17 are respectively connected, the short link 16 being also connected at 18 to the wrist pin of the crank 85 disk 19, which disk is secured at 20 to the end of the motor shaft 21.

22 is an arm which has a bearing pin 23^a at one end to which the long link 17 is connected, and at the other end of the arm 22 90 is a threaded stub shaft 23 on which the indicator lever 24 is fastened, the lever 24 having a pointer 25 and the face 26 of the housing having suitable indication members 27 and 28 to indicate the different mechanism 95 positions to which the lever 24 is to be moved in order to effect either the percussion or the brush stroke. If desired, a spring 29 may be introduced between the lever 24 and the housing 3 to hold the parts with retaining 100 friction and thereby maintain the arm 22 in any position to which it may be set by the lever.

In practice, when the lever 24 is set at position B the stroke imparted to the applicator arm 10 will be a brushing or rocking stroke, whereas when the lever 24 is set to the position A, a percussion stroke will be

imparted to the applicator arm 10. When the lever 24 is set between the two extremes, a combination of these two movements can be obtained, shading off one into the other 5 accordingly as the lever 24 is approaching one extreme position or the other.

The provision of the leather or other flexible packing 7 enables lubricant to be applied to the moving parts in the casing without 10 danger of its running down and following down the applicator arm or rod 10.

What we claim is:

1. In a vibrator, a support, a driving shaft relatively fixedly located in said support, a crank disk on said shaft, an applicator arm having bearing in said support, and a variable-stroke connection between said crank disk, said arm and said support, whereby said arm may have a percussion stroke or a 20 brushing stroke or any combination of these strokes within the extreme limits of the respective strokes imparted to it.

2. In a vibrator, a support, an applicator arm having longitudinal and oscillatable bearing in said support, a drive shaft relatively fixedly located in said support, a connection between said drive shaft and said arm, and means for varying the effective action of said connection to increase or 30 decrease the degree of longitudinal and simultaneously decrease or increase the degree of oscillatable motion imparted to said applicator arm.

3. In a vibrator, a support, an applicator arm having longitudinal and oscillatable bearing in said support, a drive shaft, a connection between said drive shaft and said arm, and a shiftable device connected with said applicator arm to increase the 40 amplitude of the oscillating motion and simultaneously decrease the degree of the longitudinal motion imparted to said applicator arm according to the position of said shiftable device.

4. In a vibrator, a support, a drive shaft, an applicator arm having bearing in said support, a crank disk on said shaft, a link between said crank disk and said arm, a shiftable fulcrum, and a link connecting 50 said shiftable fulcrum with said applicator substantially as shown and for the purposes described.

5. In a vibrator, a support, said support including a housing having a neck provided with a spherical bearing seat, an applicator arm projected through said neck in said housing, a bearing bushing on said arm having a spherical bearing surface to engage said seat, resilient means for holding 60 said bushing seated, a driving shaft having a crank disk, a link connection between said crank disk and said applicator arm, a shiftable fulcrum, and a link connection between said shiftable fulcrum and said applicator arm whereby the stroke and 65

oscillation of said applicator arm may be varied.

6. In a vibrator, a support, said support including a housing having a neck provided with a spherical bearing seat, an applicator arm projected through said neck in said housing, a bearing bushing on said arm having a spherical bearing surface to engage said seat, resilient means for holding 70 said bushing seated, a driving shaft having a crank disk, a link connection between said crank disk and said applicator arm, a shiftable fulcrum, a link connection between said shiftable fulcrum and said applicator arm whereby the stroke and oscillation of said applicator arm may be varied 75 and a lever for shifting said fulcrum.

7. In a vibrator, a support, said support including a housing having a neck provided with a spherical bearing seat, an applicator arm projected through said neck in said housing, a bearing bushing on said arm having a spherical bearing surface to engage said seat, resilient means for holding 80 said bushing seated, a driving shaft having a crank disk, a link connection between said crank disk and said applicator arm, a shiftable fulcrum, a link connection between said shiftable fulcrum and said applicator arm whereby the stroke and oscillation of said applicator arm may be varied 85 and a lever for shifting said fulcrum, and a pointer carried by said lever, said housing having position indicating marks 90 coöperative with said pointer.

8. In a vibrator, a support, said support including a housing having a neck provided with a spherical bearing seat, an applicator arm projected through said neck in said housing, a bearing bushing on said arm having a spherical bearing surface to engage said seat, resilient means for holding 100 said bushing seated, a driving shaft having a crank disk, a link connection between said crank disk and said applicator arm, a shiftable fulcrum, a link connection between said shiftable fulcrum and said applicator arm whereby the stroke and oscillation of said applicator arm may be varied, a lever for shifting said fulcrum, and a pointer carried by said lever, said housing having position indicating marks 105 coöperative with said pointer.

9. In combination with an electric motor having a casing and a driving shaft, a housing secured to said casing over the end of said driving shaft, a crank disk on said driving shaft, said housing having a bearing surface, a bushing having a bearing surface to coöperate with the bearing surface of the housing, means for maintaining said bushing seated in the housing, an applicator shaft reciprocably mounted in said bushing, a link connecting said applicator shaft with said crank disk, a lever having a stub shaft journaled in said hous- 110 115 120 125 130

ing, a link between said lever and said applicator arm, and means whereby said lever may be shifted to change the position of said last named link to thereby vary the effective action of said crank disk on said applicator arm according to the position of said lever.

10. In combination with an electric motor having a casing and a driving shaft, a housing secured to said casing over the end of said driving shaft, a crank disk on said driving shaft, said housing having a bearing surface, a bushing having a bearing surface to coöperate with the bearing surface of the housing, means for maintaining said bushing seated in the housing, an applicator shaft reciprocably mounted in said bushing, a link connecting said applicator shaft with said crank disk, a lever having a stub shaft journaled in said housing, a link between said lever and said applicator arm, means whereby said lever may be

shifted to change the position of said last named link to thereby vary the effective action of said crank disk on said applicator arm according to the position of said lever, and means connected with the stub shaft of said lever whereby said lever may be shifted from the outside of said housing.

11. In a vibrator, a support, a driving shaft relatively fixedly located in said support, a crank disk on said shaft, an applicator arm having bearing in said support, and a variable-stroke connection between said disk, said arm and said support, and means whereby the stroke of said connecting device may be varied to produce a combination brushing-percussion stroke in which the brushing stroke value may have a greater or lesser value than the impacting stroke value, as desired.

GEORGE P. ELMEN.
GEORGE SHARPNACK.
